SEAT BELT BUCKLE

Frank L. Davis, College Point, N.Y.
 (30 Mariners Lane, Northport, Long Island, N.Y.)
 Filed Apr. 27, 1962, Ser. No. 190,576
 8 Claims. (Cl. 24-77)

The invention herein disclosed relates to belt buckles, particularly for use on safety belts.

Objects of the invention are to provide a practical efficient buckle which can be made up substantially entirely of sheet metal parts and which, while strong and durable, will be small in size, light in weight and consist of but relatively few, simple, readily assembled parts.

These and other desirable objects have been attained by a novel combination and arrangement of parts in which the hand lever for effecting release is pivoted in the frame of the buckle by having slots of triangular formation engaged over the pivoted end portions of a locking bar and the latter has these end portions pivotally engaged in triangular slots in the side walls of the frame, enabling this bar thus to serve, in addition to locking purposes, the further function of a pivotal mounting for the release lever.

Other important novel features of the invention are set forth and will appear in the course of the following specification.

The drawings accompanying and forming part of the specification illustrate a present practical embodiment of the invention. Structure however may be modified and changed as regards the immediate illustration, all within the true intent and scope of the invention as hereinafter defined and claimed.

FIG. 1 is a side elevation of the buckle, with the webbing shown broken away.

FIG. 2 is a top plan view of the same.

FIG. 3 is a longitudinal sectional view on substantially the plane of line 3-3 of FIG. 2.

FIG. 4 is a side elevation showing the buckle in the released position, with the side of the frame broken away to show position of parts.

FIGS. 5 and 6 are views of opposite ends of the buckle.

FIG. 7 is a cross sectional view on substantially the plane of line 7-7 of FIG. 3.

FIG. 8 is a longitudinal sectional view on substantially the plane of line 8-8 of FIG. 7, showing parts in the closed, secured relation.

FIG. 9 is a top plan, part sectional view showing the belt end fitting separated from the buckle.

FIG. 9a is a broken plan showing how the locking bar engages over the end fitting.

The base or frame of the buckle is shown as a single sheet metal piece of U cross section having a flat back 10 and upstanding parallel side walls 11, 12.

The release lever or cover likewise is a single piece of sheet metal of reverse U-shaped cross section having a generally flat or somewhat rounded back portion 13 and dependent parallel side walls 14 spaced to easily fit between the side walls of the frame.

These companion side walls of frame and cover have triangular slots 15, 16 registering when the cover is in closed position as in FIGS. 1 and 3 and disposed with the apex of such triangles directed toward the adjacent end of the buckle.

Pivotedly engaged in the triangular slots 15 in the frame is a locking plate 17 having end portions 18, 19, FIG. 9, of reduced width to fit in the triangular slots and a downwardly extended mid-length portion 20 to enter the locking notch or opening 21 in the fitting 22 on the end of the belt webbing 23.

The pivotal or journal portions 18, 19 on the ends of

2

the lock bar 17 are of sufficient extent to carry the side flanges 14 of the cover, these reduced portions extending through the triangular slots 16 thus to pivotally confine the cover in place in the frame.

5 The lock bar is yieldingly pressed downwardly toward the back of the frame by a spring 24 of flat material shaped in V formation, as shown in FIGS. 3, 4 and 8, confined between the lock bar and a guide bar 25 which is secured between the side walls of the frame.

The spring is secured in this relation by engagement of a lug 26 on the guide bar 25 in an opening 27 in the upper portion of the spring and by engagement of an angularly turned lug 28 on the lower end of the spring in an opening 29 in the lock bar.

The spring is shown as having an upwardly extended end 30 engageable by the cover to hold it against rattling.

The guide bar is shown as arched in the central portion at 31 to provide clearance for the lower portion of the lock bar and as having portions 32 at the ends of the same closely approached to the back of the frame to serve as confining guides for keeping the end fitting closely confined in the frame.

15 The guide bar 25 is shown supported in the frame by engagement at its opposite ends in slots 33 in the side walls 11 and 12 and by having one end slightly inclined at 34 and the opposite end peened over at 35.

The web 36 forming the opposite end of the belt is shown looped about a tensioning bar 37 and under a snubbing bar or pin 38, both of which are slidably and non-rotatably confined by flat end extensions 39, 40 engaged in slots 41, 42 in the opposite side walls of the frame.

25 The flattened ends 39 of the tensioning bar are shown extended in FIG. 9 to form finger holds by which this bar may be slid away from the snubbing bar 38 for free adjustment of the webbing.

The adjustment bar 37 is shown in FIG. 9 as knurled or roughened to gain a firm holding grip on the webbing when tensioned toward the snubbing bar 38.

30 In the normal position of parts the V-bent spring 24 holds the lock bar 17 tensioned downward or inwardly, FIG. 8, toward the back 10 of the frame, with the flat end portions 18, 19 of the lock bar engaged with the lower edges of the triangular slots 15, 16 in the side walls of the frame and the dependent side flanges of the cover respectively. In this way the cover is yieldingly held downward in the closed position shown in FIGS. 3 and 8.

35 On entry of the end fitting 22 into the end of the buckle frame the lock bar will be forced upwardly against tension of the spring until the fitting has been fully entered in the buckle to the point where the end of the lock bar can drop into the locking notch 21, the position shown in FIG. 8, in which position the fitting will be securely locked and held in the frame of the buckle.

40 In this locked condition the end fitting 22 is confined beneath the end portions 32, FIG. 7, of the guide bar 25 and beneath overstanding shoulders 43, 44 on the edges of the lock bar at opposite sides of the tongue 20 at the lower edge of this bar.

45 Accidental escape of the end fitting is thus positively prevented and the parts are held against looseness or rattling.

The lower edges of the triangular notches 15 in the side walls of the frame limit downward movement of the lock bar in the frame and the upper edges of these 50 slots limit upward swinging movement of this bar.

The lower edges of the triangular notches 16 in the side flanges of the cover, by engagement with the inwardly tensioned lock bar, serve to hold the handle in the normally closed position, FIG. 3.

55 The upper edges of the triangular slots 16 in the cover flanges afford clearance for the lock bar to be pushed upwardly under the lifting pressure of the end fitting be-

ing entered in the end of the buckle so that this fitting may be engaged in the buckle without forcing the cover or handle into opened position.

The construction disclosed enables the buckle to be made small and light in weight without sacrificing strength or safety factors.

All parts, except the adjusting and snubbing bars 37, 38, may be made of sheet metal with consequent advantages in cost, holding power and light weight and the like.

The flat journal extensions 18, 19 of the lock bar 17 are of a width approximating the length of the upper and lower edges of the triangular slots and the base line connecting these side edges may be curved as indicated at 46 on an arc having its center at the apex of the triangle thus to confine the lock bar against edgewise movement in the frame and the edges of the reduced journal portions may be rounded to afford smooth rolling action of this bar.

Similarly the lower edge of the lock bar may be rounded as shown to ride over the face of the end fitting and drop into position in the inserted end fitting.

The frame and the cover, in the channel form shown, may be made of light sheet metal without sacrificing strength. The lock bar may be made of somewhat heavier stock to assure sufficient locking engagement with the end fitting.

The pivoting of the flat end extensions of the locking bar in the triangular slots in the frame and the pivotal engagement of the cover on these end extensions eliminates the need for a pivot bolt and spring such as heretofore used in buckles of this general type.

The single V-bent spring serves to secure the lock bar and cover together in properly assembled relation, eliminating need for any special fastenings.

The buckle is closed by simply pushing the end fitting on the web into the end of the buckle, where it is automatically caught by the spring tensioned locking bar and the parts can be instantly released by simply raising the cover sufficiently to lift the lock bar from holding engagement with the end fitting.

Assembly of the buckle is simple and securing of the parts is effected by the simple act of assembly.

Referring to FIG. 9 the longer extension 19 of the locking bar is first passed upwardly through slots 16, 15 in the cover and base flanges and then the bar is shifted down to pass the lower, shorter extension 18 through slots 16, 15 at the bottom.

The guide bar 25 then may be inserted between the side flanges 11, 12 of the frame in an inclined position and with the bent end 34 engaged in the lower slot 33 this bar may be rocked into alignment and then be shifted into engagement in the upper slot 33.

FIG. 9 shows the lower bent end of the guide bar as longer than the upper end so that this bar may be shifted downward through the lower slot to permit of the necessary rocking movement to bring the upper end into alignment with the upper slot.

Thus, whereas the locking bar has a longer upper end 19 the guide bar 25 has in effect the reverse, a longer, lower end.

These parts can then be locked against releasing movement, that is the locking bar against upward shifting movement and the guide bar against downward shifting movement by engagement of the spring 24 between these parts, the spring then acting as a key locking both bars against release shifting movements.

As an additional safety precaution the upper end of the guide bar 25 may be peened over as shown at 35.

Similarly the web securing pins 37, 38 are secured by the mere act of assembly.

After looping the web about it the first pin 37 is engaged, in an inclined relation in the slots 41, 42 in the sides of the frame.

Then with the webbing crowded toward one end of this pin clearance is provided for inclining the second pin 38 sufficiently to engage the ends of it in the slots and whereupon the webbing then when straightened out will hold the pins in the cooperating relation shown.

What is claimed is:

1. A seat belt buckle comprising
a frame of channel form having a back wall and up-standing parallel side walls,
said side walls having opposed triangular slots,
a release handle of channel formation having reversely
extending side flanges entered between said side walls
and having triangular slots corresponding to and in
alignment with said triangular slots in the side walls
when said handle is in closed position in the frame,
a locking bar having end portions of reduced width
extending through said triangular slots in said side
walls and side flanges and having a locking tongue
at the free edge of the same opposed to the back wall
of the frame,
a spring tensioning said locking bar toward said back
wall of the frame and
a web end fitting insertable over said back wall between
said side walls into position beneath said spring ten-
sioned locking bar and having a locking recess dis-
posed for entry of said locking tongue therein.
2. The invention according to claim 1 with a guide bar
extending across between said side walls and said spring
being engaged between said guide bar and said locking
bar.
3. The invention according to claim 1 with a guide bar
secured between said side walls and said spring being of
V formation and in engagement at one end with said
guide bar and in engagement at the opposite end with
said locking bar.
4. The invention according to claim 1 in which said
locking bar is a flat plate and in which said reduced end
portions are of a width substantially equal to the length
of the side edges of said triangular slots.
5. The invention according to claim 2, in which one
of said end portions of the locking bar is longer than the
other and in which said guide bar has a longer end por-
tion at the opposite end of that bar from the longer end
portion of the locking bar and in which said spring is
interlockingly engaged with said bars to prevent move-
ment of said bars in the direction of the longer end por-
tions of the same whereby thus to secure both bars against
shifting movement in the frame.
6. The invention according to claim 1, with a guide
bar overstanding said locking bar and said spring being
interposed between said guide bar and locking bar and
having an extension positioned for engagement by the
cover to hold the cover against rattling.
7. The invention according to claim 1, with a guide bar
overstanding said locking bar, said spring being interposed
between said guide bar and locking bar, said guide bar
having an angularly bent end engaged in one side wall of
the frame and having the opposite end peened over in
the opposite side wall of the frame.
8. The invention according to claim 1, with said side
walls having opposed longitudinal slots in the ends re-
moved from said triangular slots, web securing pins having
flat end extensions slidingly engaged in said longitudi-
nal slots and webbing looped about the innermost of said
slidably mounted pins and extending between said pins.
